UNITED STATES PATENT OFFICE

REGINALD A. FESSENDEN, OF CHESTNUT HILL, MASSACHUSETTS, ASSIGNOR TO SUB-
MARINE SIGNAL COMPANY, OF PORTLAND, MAINE, A CORPORATION OF MAINE

METHOD AND APPARATUS FOR COORDINATING RADIO AND PHONOGRAPH
REPRODUCTION

Original application filed May 21, 1924, Serial No. 714,899. Divided and this application filed September
13, 1927. Serial No. 219,351.

My invention relates to improving the efficiency of radio and wire telephone and phonograph reproduction, and more especially to co-ordinating these methods of reproduction, 5 (and similar means, as reproduction from different radio stations), and still more especially to convenience in said co-operation and to the production of new effects and results thereby.

10 The object of my invention is to accomplish said increase in efficiency and said co-ordination, and said convenience in co-ordination and operation, and said new effects and results.

15 The accompanying drawing shows, partly diagrammatically, means adapted for the carrying out of my invention.

Figure 1 shows the arrangement of apparatus and circuits.

20 Figure 2 a type of electric generator adapted for use with my electro-phonograph and

25 Figure 3 shows the application of the invention to a violin in detachable form in its relation to a violin bridge.

This application is a division of U. S. application Serial No. 714,899, filed May 21, 1924.

In Fig. 1 is shown a novel system in which a radio or wire telephone and a phonograph 30 act individually or in conjunction, and without any necessary mechanical connection between the phonograph record and the device emitting the sound, i. e. the reproducer; here shown as a piano 39. Here 20 is the 35 phono-electric generator, whereby the minute electric impulses are produced in the circuit 37', 34, by the relative motion of the record 28, either optically as shown in U. S. applications Serial No. 685,699, filed

40 March 23rd, 1912, and Serial No. 42,856, filed July 29th, 1915, and Serial No. 635,362, phonograph-kinetoscope, filed July 26th, 1911, and Serial No. 423,186, filed Nov. 10th, 1920, (but which optical methods and appa-

45 ratus are not claimed herein); or as shown, and more fully and in detail in Fig. 2, mechanically by the action of the phonograph needle 8; or in any other suitable manner.

The disc 28 is driven by the electric motor 50 36, whose speed is regulated as desired by

the adjustable resistance 37, or other suitable means. 37' is an adjustable impedance for regulating the strength of the electric impulses in the circuit, and hence the strength of the reproduction in the piano-speaker 39. 55

30 is the circuit of the wireless or wire telephone line; 33 is an amplifier operating the piano speaker 39, described below. 34 and 30' are transformers for putting the phono-electric generator and the telephone circuits 60 in operative relation to the amplifier.

32 is a switch. When it is thrown to the right, on to the contact 32', the wireless telephone is cut out, and only the phonograph record is heard. When it is thrown to the left, to contact with 33', the phonograph is cut out and at the same time, by reason of the insertion in the circuit thereby of the compensating coil 33', or other suitable means, the tuning of the wireless circuit is maintained unchanged. When the switch is in the intermediate position, as shown, both wireless and phonograph act conjointly and a soloist on the wireless may be accompanied by a full orchestra on the phonograph, or vice versa, speed being regulated by 37 and relative intensity by 37'. 45 is a switch whose function is described below. 65

70 Fig. 2 shows a suitable form of phono-electric generator more in detail. Here a coil 210 of light weight is fastened to the phonograph needle, as shown, and being moved back and forth in the field of the magnet 190 by the motion of 8, pivoted at 27 and actuated by the revolving phonograph disc 28, generates currents which are carried to the reproducer 18, as shown. 75

By this invention a number of entirely new and very useful results are obtained, e. g.

It enables one to accompany a broadcast 90 solo by McCormack, "That Old Refrain" for example, by a phonograph record of Kreisler's (the composer's) rendition on the violin of the same composition, and to modulate the strength of the accompaniment at every instant, and instantaneously, to suit the momentarily varying strength of the broadcast of the soloist; the tempo being similarly varied to coincide with that of the broadcast; or to supplement the rendition by Dam-

rosch and his orchestra of "Evening Star" from Tannhauser over the radio by Caruso's voice from a phonograph record; or to hear Caruso and McCormack sing together the 5 same famous song, a possibility of great value in the study of singing.

Since the same loud speaker is used, e. g. applicant's piano loud speaker, and actuated in the same way, i. e. by the same loud speaker mechanism, and all scratching and static and other abrupt disturbing impulses are 10 eliminated accurate and satisfactory comparison and accompaniment is rendered possible, which is of course not possible where the 15 loud speakers are of different types, or operated by different types of mechanism, e. g. one by a mechanically acting lever and the other by an electromagnetic mechanism, or there are disturbing impulses.

20 The listener may himself accompany the radio or phonograph by playing on the piano, and the effect is much more natural and agreeable, as both sounds come from the same location in the room. The desired changes in 25 modulation may be made instantly and by one seated at a distance, in place of one standing beside the phonograph loud speaker; and without danger of injuring the record, by merely shifting the element 37.

30 Another advantage is in shifting phonograph records at a distance from the loud speaker without the necessity of employing special mechanism. One may be seated in a 35 chair on the opposite side of the room from the piano loud speaker, and listening to the radio. A broadcast may come in which might be accompanied by a phonograph record. If the phonograph motor and disc table is at the elbow, all that is necessary to place the 40 desired disc on the rotating table, and adjust the speed and then the modulation by moving 37, 37'. And the modulation may be made such that the phonograph record is 45 reproduced many times louder than any standard type of phonograph could do, or adjusted more delicately and softly, or loudly and softly on the same record, to accompany the radio, without moving from the seat. And if the micro-photo-phonographic 50 records are used, described and claimed in Serial No. 423,186, filed Nov. 10th, 1920, the storage and handling and costs of the records is much reduced.

55 The type in which an independently playable musical instrument with strings such as a piano is used, enables the listener to accompany either the radio or the phonograph or both combined, himself. This is of great 60 value to students on these instruments. A student can compare his own touch on the piano with that of the greatest living masters of the art; or of those long dead. By the use of an area source, such as the piano, the necessity of having the phonograph disc 65 driving apparatus and the radio apparatus

in the same part of the room is obviated. The wireless apparatus is often best located in one part of the room, near a window, while the phonograph discs may be more conveniently located near a fire place or electric reading lamp. Or one member of the household who may prefer to sit in one place, may prefer the radio and another, who may prefer to sit in another, may prefer the phonograph. With the area source, both will hear both reproductions equally well, no matter where they may sit.

70 By the use of the piano as loud speaker, absolutely correct reproduction is obtained and static and scratching is cut out.

75 By this system the power required for driving the phonograph discs is much reduced and the whole outfit may be driven from dry cells; a matter of importance where no electric power circuits are available.

80 It is preferred that the thrust of the moving part of the electromagnetic or other mechanism which operates the loud speaker against the diaphragm or its equivalent should be opposed, not by a spring or other device having a natural period, but as shown in Fig. 5 of the parent application, by inertia, and that the only substantial restoring forces should be those inherent in the diaphragm or its equivalent. This has been 85 found to give, for reasons not here disclosed, much better results.

90 When the switch 45 is thrown, and the piano is played upon, the loud speaker mechanism acts as a generator and the music played is transmitted through the circuit 46 to any place desired, for example to another room in the house.

95 This reverse action of electromagnetic mechanism is well known. An example is the telephone receiver which may be used to transmit electric waves as well as to produce sound waves. When acting as a producer of electric waves, all that is necessary is to have an initial magnetization of the wire, 43. If it is not desired to do this by permanent magnetization, it may be done by passing a 100 slight direct current in the coil 50. The wire 43 having its magnetization or permeability changed by the action of the acoustic waves on it varies the flux threading the coil 50 and thereby induces an electromotive force in it corresponding to the acoustic waves. In this 105 manner the piano may act as a source of sound in producing electric current and may therefore be said to generate electromagnetic waves.

110 By the term "electro-phonograph" is meant a phonograph in which the recorded sounds are first transformed into electric impulses before being reproduced; and includes the elements necessary for generating the electric impulses from the phonograph records.

115 Applicant, in his investigations on cutting out scratching, static, and abrupt disturb-

ing impulses generally, by the use of a plurality of resonant elements, discovered that even a violin, with only four strings, though not cutting out static to any useful extent, when used as a loud speaker for electric phonographs, cut out a part of the scratching from the phonograph discs. Applicant then discovered (amongst other ways) that by adding additional resonant elements, for example, reeds attached to the violin bridge, substantially all the scratching could be cut out. He further found that if the number of reeds was made sufficiently numerous, such a violin loud speaker would even cut out substantially all of the static when used for receiving radio broadcasting.

Applicant then discovered that a piano could be used for receiving radio broadcasting, and that it had a sufficient number of resonant elements attached to its sound board, i. e. the piano strings, to act extremely efficiently as a static eliminator, in addition to other properties, i. e. that of giving absolutely faithful reproduction of all sounds, from the lowest to the highest, and of giving equal intensity of sound in all parts of the room. As an illustration of the efficiency of the piano as a static eliminator, during the past three summers, applicant, who has one in his house, and the members of his household and guests, have never heard static or known that there was any static, except on such occasions as they listened in on other types of apparatus, to ascertain the atmospheric conditions. Reports of other tests, e. g. by the U. S. Navy, will be found in the "Boston American" for August 28, 1924, with photographs of the apparatus and description of the mechanism attached to the back of a piano, and other details.

The piano loud speaker 39 of Figure 1 may have its sound board set in vibration by the electric telephone impulses in any suitable way, since the essential feature of its efficiency as a loud speaker lies in the conjunction of the sound board with the plurality of resonant elements, i. e. piano wires. In most cases, e. g. as in the "Boston American" reference to August 28, 1924, any good speaker mechanism is simply wired into the back of the piano, and its vibrating element fastened to the back of the sound board.

Fig. 3 shows another form. Here 50 is a violin and 51 is its bridge; 55, 55, 55, 55, are the violin strings. 52, 53, 54 are vibrating reeds, weighted on the ends as shown and of such dimensions, best found by experiment, that they have a predetermined amount of dampening, preferably, in most cases, an amount approximately equal to that of the violin strings; and attached to the bridge, as shown. The natural periods of the auxiliary vibrators 52, 53, 54 are preferably different from those of the strings and preferably above and below those of the strings.

The violin is preferably driven or excited by a sideways pull of the wire 59, as applicant has discovered, contrary to what has heretofore been taught, that the main mode of action of a violin is a rocking of the bridge and not an up and down motion, and that the efficiency of a violin can be much increased by attaching a vertical strip of thin wood to the underneath side of the top of the violin, and running longitudinally, so as to act, as a sort of a fan when the bridge is rocked in playing.

The wires 59 and 59' are preferably of soft iron or nickel and are screwed into the circular spring 60, of magnetic material, so as to leave a small air gap between them, as shown. 22, 23 are as before a magnetizing coil and a source of current and 61 is a coil connected as shown to leads 63, leading to the transmitter, or receiver. 62 is a small ball, used as an inertia to oppose the pull on the bridge when the two wires 59, 59' are attracted together by the action of the currents flowing in the coil 61, coming from the transmitter.

Similarly, when the violin is played upon, the wire 59 approaches and recedes from the wire 59', thereby generating electric currents which flow out into the line 63 and actuate the receiver.

Applicant has, by means of his Wollaston wire galvanometer, described in U. S. Patents 979,145 and 1,045,782 and elsewhere, plotted curves showing the sound efficiency of different musical instruments at different frequencies; and has found that the violin and piano have substantially straight line efficiency curves, and horizontal i. e. the efficiency of these instruments (and also, approximately, that of the violincello and bass viol) is substantially constant over their range.

Applicant has also found that these act as "area sources" and consequently when arranged as shown, act as "pick-up" in such manner that if placed on a stage, the actors may walk about and yet be heard equally well, substantially, independent of their location. And in taking phonograph records of singers and orchestras, there is no necessity of the singer leaning backwards and forward as he sings, or of placing the instruments in definite positions. And in reproducing all those in the room can hear substantially equally well.

Applicant has found that the "pick-up" and reproduction of these instruments so arranged and employed as shown, and in similar manner, is immeasurably better as regards articulation and naturalness of tone than the loud speakers on the market. With this form of "pick-up" and reproducer the speech and singing are indistinguishable from those of the individual when in the room.

Applicant has discovered that owing to the

presence of the plurality of naturally resonant elements, and damped properly, as determined by experiment, by adjusting the mass and dimensions and elasticity of the vibrating elements and their frictional losses, substantially all disturbing noises, "atmospheric scratching" and the like are cut out. The theory is not definitely known, it being a matter of discovery and observation, but it, i. e. the effect, is probably due to the fact that abrupt noises do not act in sustained synchronism, and hence do not set the vibrating elements swinging to anything like the degree that sustained vibrations do. In the violin, e. g. when arranged as shown and described, and acting as loud speaker, the noises coming in on a night of "bad atmospheric" are not only changed from a low pitched rumble and crash to a few crackles, but the pitch is raised substantially above that of the highest string on the violin. And by applying several vibrating elements of pitches approaches inaudibility, as 53, 54, in Fig. 6, the disturbances remaining are substantially too high pitched to be substantially appreciable, and the broadcast comes in very plainly.

Better results are, however, obtained by the arrangement shown in Figure 1, in which a nickel or iron wire 43 is fastened at each end to adjustable tuning pins 41, 42, stretched over bridges 40, 40', and the received telephonic currents flowing through the coil 50 vary the magnetization of the wire 43, and change its length by the well known magnetostriction effect, thereby bending the sound board in and out, and causing the whole sound board to act as a unitary large diaphragm. By employing a number of such wires 43, and suitably arranging them, as shown in another co-pending application, the piano sound board and wires are made so that they have no detrimental selective resonance. The advantage of using the adjustable tuning pins 41, 42, is that by proper stretching of the nickel wire, the magnetostriction effect is greatly improved, and made uniform.

By the expression "operable selectively" by the phonograph or wireless, is meant operable by either one or the other, as desired. By the term "operable jointly" is meant operable by both of them together and simultaneously.

By area source of sound I mean source of the kind described in my U. S. Patent 1,277,562, Sept. 3rd, 1918, i. e. having a diameter of more than seven inches. By the combination herein described new technical effects are produced.

60 What I claim as my invention is:—

1. In a system of the kind described, a pick up device including an area source and a plurality of substantially parallel resonant elements operated directly thereby, said pick up device including a vibratable element ar-

ranged substantially perpendicular to said resonant element.

2. In a system of the kind described a pick up device including a violin having a bridge and a vibratable element attached thereto and operated in the longitudinal direction of said bridge. 70

3. In a system of the kind described, a pick up device comprising a violin having a bridge, a resonant element contacting therewith and a current varying device operated directly by said bridge. 75

4. In a system of the kind described, a pick up device comprising a violin having a bridge, a resonant element contacting therewith and a magnetophonic pick up unit having its vibratable element attached to said bridge. 80

5. In a system of the kind described, a pick up device comprising an area source having a plurality of resonant elements extending one way and a magnetophonic pick up unit having its vibratable element operatively connected with said resonant element, said vibratable element vibrating in a direction transverse to said resonant elements. 85

6. In a system of the kind described, a loud speaker having a plurality of resonant elements, a bridge on which said elements rest, and a loud speaker unit having its vibratable element attached to said bridge element. 95

7. In a system of the kind described a loud speaker including a violin and a loud speaker unit having its vibratable element attached to said violin. 100

8. In a system of the kind described, a loud speaker including a violin and a loud speaker unit having its vibratable element attached to the bridge of said violin. 105

9. In a system of the kind described, a loud speaker including a violin and a loud speaker unit having a longitudinally vibratable rod attached at one end to the bridge of said violin and at the other end to means for impressing compressional waves thereon. 110
